(57) **CLAIM**

The ornamental design for a toilet stool, as shown and described.

DESCRIPTION

FIG. 1 is a front, right, top, perspective view of a toilet stool, showing my new design;

FIG. 2 is a front, left, bottom, perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof;

FIG. 9 is a front, right, top, perspective view of the toilet stool in a folded configuration; and,

FIG. 10 is an exploded, front, right, top, perspective view of the toilet stool in an unfolded configuration.

The broken lines in the drawings illustrate the portions of the toilet stool, which form no part of the claimed design.
